FLUSHING APPARATUS FOR WATER-CLOSETS.

1,267,923.

Specification of Letters Patent.

Patented May 28, 1918.

Application filed March 24, 1915. Serial No. 16,740.

To all whom it may concern:

Be it known that I, JOHN B. R. SMITH, a citizen of the United States, residing at Hamilton, in the county of Baltimore and State of Maryland, have invented new and useful Improvements in Flushing Apparatus for Water-Closets, of which the following is a specification.

This invention relates to improvements in flushing apparatus for water-closets, and proposes a construction of the "frost-proof" type, the chief characteristics of which are that the flush tank and the water supply and discharge pipes are normally empty; the admission of water to said tank is controlled by a normally closed main valve which is suitably located underground below the frost line; and the said main valve is employed in combination with an auxiliary valve which is normally open but is automatically closed during the period in which the main valve is open and is used to control the water flowing past the main valve, causing said water to pass into the flush tank so long as the main valve is open and thereafter and when the main valve is closed permitting it to pass through the flush pipe.

The objects of the invention, briefly stated, are to provide a construction of the type described having improvements in the organization of its parts whereby those parts which are exposed to the atmosphere and are located adjacent the closet bowl or hopper are not subject to frost and are certain and reliable in their operations at all times and under all conditions and whereby the flow of water to the closet bowl or hopper is substantially free or unobstructed.

With the above and other objects in view the invention consists in certain detail features of structure, combination and relation which will be pointed out as the description proceeds.

An embodiment of the invention is illustrated in the accompanying drawings, wherein:

Figure 1 is a side elevation illustrating a practical application of the invention where in the opening and closing operations of the main and auxiliary valves are controlled by the closet seat;

Figs. 2 and 3 are vertical longitudinal sectional views, Fig. 2 showing the valves in their normal positions, and Fig. 3 showing

the valves in the positions which they assume when the closet seat is depressed; 55

Fig. 4 is a detail plan view showing more particularly the relation between the flushing apparatus and the hinged bracket which carries the closet seat; 60

Fig. 5 is a detail longitudinal sectional view of the upper portion of the flushing apparatus showing more particularly the arrangement of the spring by which the valves are held in their normal positions; 65

Fig. 6 is a detail longitudinal sectional view of the lower portion of the flushing apparatus, showing more particularly the construction and relation of the main and drain valves and of the inlet and drain ports. 70

Similar characters of reference designate corresponding parts throughout the several views.

The closet bowl 1 is of any suitable construction and is equipped with a seat 2 which normally occupies an inclined position. The water which flushes the bowl is stored in a normally empty tank 3 having a pipe 4 through which water both enters 80 and discharges from said tank. The bowl 1 is equipped with a flush pipe 5 and the pipes 4 and 5 are connected to a normally empty supply pipe 6 which projects for some distance into the ground, near its lower end 85 having a lateral connection 7 with a water main and at its lower end having a connection 8 with a drain pipe. In this connection it may be noted that the expression "the pipe 6" is adapted to designate all the assembled 90 alining elements which extend between the drain connection 8 and the flush pipe 5 and, hence, is to be understood as including, not merely the main section 6^a of the pipe 6, but the valve casing 6^b secured at the lower 95 end of the section 6^a and carrying the connections 7 and 8, the casing 6^c from which the flush pipe 5 leads and the union 6^d which connects the section 6^a and the pipe 4 and the section 6^a and the casing 6^c. 100

The pipe 5 is arranged above the pipe 4; and the pipe 6 is provided intermediate the pipes 4 and 5 with a valve seat 9 to coact with a valve 10 mounted upon a stem 11. The stem 11 extends through the pipe 6 and carries at its lower end the main valve 12 and the drain valve 13. That portion of the stem 11 upon which the valves 12 and 13

are secured and which is shown at 11^a is suitably connected for universal movement to the body of the stem at a point slightly above the main valve 12. The universal connection between the body of the stem 11 and the portion 11^a preferably and conveniently consists of a transverse pivot pin 14 carried by the part 11^a and passing loosely through a somewhat larger opening in a lug 15 provided at the lower end of the body of the stem 11. This method of connecting the body of the stem 11 and the portion 11^a of the stem allows of said portion 11^a having universal movement within the limits in which such movement may be necessary, under certain conditions, to insure of the effective seating of the valves 12 and 13.

The valves 12 and 13 are of piston or cylindrical form, being cupped, and confronting one another. Said valves are conveniently secured on the stem part 11^a by the clamping coaction of washers 16 threaded upon the part 11^a and flanges 17 fixed on the part 11^a.

That portion of the pipe 6 within which the valves 12 and 13 slide has an internal diameter exactly conforming to the external diameter of said valves whereby the latter have a tight sliding fit. Normally the valve 12 has a position adjacent the upper side of the port at which the connection 7 opens into the pipe 6, in which position said valve interrupts communication of the pipe 7 with that portion of the pipe 6 which is located above said valve but permits the pipe 7 to communicate with the space 18 between the valves 12 and 13. When the flushing apparatus is operated, the valve 12 is moved, as will be hereafter described, to a position below the connection 7, in which position of the valve 12 said connection 7 communicates freely with the pipe 6 whereby water from the connection 7 may flow upwardly through the pipe 6 and through the pipe 4 into the tank 3.

To insure of the drainage of the pipe 6 when the valve 12 is in its normal position, said pipe has its lower portion provided with a by-pass duct 19, the lower end of which opens into the pipe 6 at a point below the drain valve 13 in the normal position of said drain valve. When the main valve 12 is moved to its lowermost position to establish communication between the connection 7 and the pipe 6, the drain valve 13 engages an annular or cylindrical seat 20 arranged intermediate the lower end of the duct 19 and the drain connection 8 and thus prevents water from passing from said duct to said drain connection. When the drain valve 13 is in engagement with its seat 20, the lower end of the duct 14 communicates with the aforesaid space 18 between the main and drain valves 12 and 13.

The main valve 12 is normally in its

closed position and the auxiliary valve 10 is normally in its open position. However, when the main valve is moved to its lowermost position, for convenience termed its "open" position, the auxiliary valve 10 is closed and, hence, the water which flows into the pipe 6 from the connection 7 will pass through the pipe 4 into the tank 3, as above described, instead of passing into the hopper. But when the normal relation of the valves is restored, that is, when the main valve 12 is moved into its normal closed position and the auxiliary valve 10 is moved into its normal open position, the water stored in the tank 3 during the period of closure of the valve 10 flows from said tank through the pipes 4, 6 and 5 into the hopper, flushing the latter.

The stem 11 projects beyond the upper end of the pipe 6 and through a cylindrical head 21 mounted on the upper end of the pipe 6, the head 21 being provided with a stuffing box 22 surrounding said stem and preventing water from flowing into the head 21 from the pipe 6. The stem 11 is operated in one direction by an expansive coil spring 23 and in another direction by the hinged bracket 24 which carries the seat 2. The spring 23 is arranged within the head 21 in surrounding relation to the stem 11 and bears at its lower end against the base of the head 21 and at its upper end against a collar 25 suitably secured on the stem 11. For the purpose of enabling an operation of said stem by the bracket 24, the stem carries a hood or equivalent device 26 which surrounds or fits over the head 21 and has at its lower end a circumscribing flange 27 extending under and engageable by the arms of the bracket 24. The collar 25 is preferably cupped and faces downwardly, its lower portion fitting within the adjacent surrounding face of the head 21.

By arranging the spring 23 above the pipe 6 and by providing against the passage of water from said pipe into the head 21, it is assured that the operation of said spring shall at all times be certain and reliable, since the action of the spring is not affected by the water which passes through the apparatus nor by frost. The arrangement of the spring 23 above the pipe 6 has a further advantage in that the water which passes to the bowl or hopper to flush the latter has a substantially free or unobstructed flow and, hence, it is assured that the flushing operation shall be highly efficient both as regards the volume and intensity of the stream.

The operation will be readily apparent from the foregoing description. The spring 23 normally holds the stem 11 and the parts carried thereby in their normally elevated positions wherein the auxiliary valve 10 is open the main valve 12 is closed and the drain valve 13 is open. When the parts

are in their normal positions any water which may have remained in the pipe 6 from a previous flush escapes from said pipe through the duct 19 and the drain connection 8. When the seat is occupied the stem 11 is operated against the tension of the spring 23 by virtue of the engagement of the arms 24 against the flange 27; and said stem and the parts carried thereby are moved into their lowermost positions wherein the auxiliary valve 10 is closed, the main valve 12 is open and the drain valve 13 is closed. When these relations obtain, water flows from the connection 7 through the pipe 6 and into the tank 3, as above explained. When the seat is released and the spring 23 raises the stem 11 and restores the valves 10, 12 and 13 to normal positions, the water which accumulated in the tank 3 during the closure of the valve 10 and the opening of the valve 12 flows from said tank into the hopper, flushing the latter, and the water in the pipe 6 escapes through the duct 19 and drain passage 8.

The valves 12 and 13 by virtue of their cup form and their confronting relation are balanced. In either position of said valves their inner circumferential faces are subject to the prevailing water pressure since in the raised positions of the valves 12 and 13 the space 18 between said valves communicates with the connection 7 and in the lowered position of the valves 12 and 13 the said space 18 communicates with the duct 19. The pressure of the water against the internal faces of the valves 12 and 13 assures of said valves being held securely against the cylindrical face of the lower portion of the pipe 6 and, hence, assures of the effective seating of the valves at all times and under all conditions. A further factor in promoting the efficient action of the valves 12 and 13 is the universal joint connection above described between the stem part 11^a and the body of the stem 11, which enables the part 11^a to have such measure of play relatively to the body of the stem 11 as will insure of the engagement of the valves 12 and 13 with the surrounding face of the pipe 6, regardless of wear and in accurate alinement with the parts which form the lower portion of the pipe 6.

The head 21 has a threaded connection with the pipe 6 and above said pipe is formed with or secured to a nut 29 which is threaded into said pipe. The diameter of the valves 12 and 13 corresponds to the minimum diameter of the pipe 6. It follows, therefore, that when the nut 29 is unscrewed from the pipe 6, the working parts of the apparatus, comprising the stem 11 and the valves 10, 12 and 13, together with the head 21, the spring 23, the collar 25 and the hood 26 may be removed as a unit for

such purposes as may be desired. The unit 65 comprising the parts specified may be replaced in the pipe 6 with equal facility and secured in position merely by screwing the nut 29 into the upper end of said pipe.

Having fully described my invention, I claim:—

1. In a frost-proof-closet, the combination with a supply pipe, a tank, a pipe connecting the tank and the supply pipe, a closet bowl, and a flush pipe connecting the supply pipe and the closet bowl, the supply pipe having a valve seat between the flush pipe and the pipe which leads to the tank, of a valve working in relation to said seat, a stem carrying said valve, a head mounted on the upper end of the supply pipe, the stem projecting into said head, a stuffing box associated with the base of the head and surrounding the stem, a collar mounted on the stem within the head, a coil spring for holding the valve in normal position and surrounding the stem within the head, one end of said spring bearing against the base of the head and the other end of said spring bearing against said collar, a hood secured upon the upper end of the stem and fitting over said head, the hood having a flange at its lower end and a hinged seat-carrying bracket having its arms arranged to engage said flanges. 95

2. In a frost-proof closet, the combination with a supply pipe, a tank, a pipe connecting the tank and the supply pipe, a closet bowl, and a flush pipe connecting the supply pipe and the closet bowl, the supply pipe having a valve seat between the flush pipe and the pipe which leads to the tank, of a valve working in relation to said seat, a stem carrying said valve, a head mounted on the upper end of the supply pipe, the stem projecting into said head, a stuffing box associated with the base of the head and surrounding the stem, a collar mounted on the stem within the head, and a coil spring for holding the valve in normal position and surrounding the stem within the head, one end of said spring bearing against the face of the head and the other end of said spring bearing against said collar, the head being threaded into said supply pipe, and having its base formed as a nut whereby the head, the parts inclosed therein, the stem, and the valve mounted upon said stem may be removed from and replaced into said supply pipe as a unit. 110

In testimony whereof I have hereunto set my hand in presence of two subscribing witnesses.

JOHN B. R. SMITH.
